DIGITAL ELECTRIC ALARM CLOCK

Alan E. Koplar, Lincolnwood, Ill., assignor to
Lava-Simplex Internationale, Inc., Chicago, Ill.

Filed Feb. 22, 1974, Ser. No. 444,851

Term of patent 14 years

Int. Cl. D10—01

U.S. Cl. D10—6

FIG. 1

FIG. 2

FIG. 1 is a top, front and left side perspective view of a digital electric alarm clock, showing my new design; FIG. 2 is a bottom, rear, and right side perspective view thereof.

I claim:

The ornamental design for a digital electric alarm clock, substantially as shown.
